UNITED STATES PATENT OFFICE.

WILLIAM C. WERMUTH, OF CHICAGO, ILLINOIS.

TROUGH ARM-SLING OR THE LIKE.

980,464.

Specification of Letters Patent. Patented Jan. 3, 1911.

Application filed June 3, 1909. Serial No. 500,020.

To all whom it may concern:

Be it known that I, WILLIAM C. WERMUTH, a citizen of the United States, residing at Chicago, in the county of Cook and State of Illinois, have invented certain new and useful Improvements in Trough Arm-Slings or the Like, of which the following is a description.

My invention is designed for the purpose of supporting the forearm, as in the case of fractures or other injury, or when because of any injury or disease, it is desirable to properly support the forearm and hand.

It is intended to take the place of the crude method generally employed which consists in a handkerchief or sling tied about the neck in the loop of which the arm or hand is loosely supported.

To this end my invention consists in the novel construction, arrangement and combination of parts herein shown and described and more particularly pointed out in the claims.

In the drawings wherein like reference characters indicate like or corresponding parts, Figure 1 is a front view of a figure showing my improved appliance in place and illustrating the preferred manner of securing the same, Fig. 2 illustrates the back of the figure showing the suspensory slings or straps crossed upon the back to firmly retain the sling in position, Fig. 3 is a front elevation of my improved sling, and Fig. 4 is a fragmentary view showing a slight modification.

In the drawings in which the preferred construction is shown, 1 represents a trough shaped part of suitable material such for example, as strong muslin cloth, which may be readily sterilized and cleansed, or of any preferred material suitable for the purpose. In the preferred construction shown one end, as at 2 is closed while the other end as at 3 is preferably open. Suitable straps 4—4 are preferably provided having one end as at 5 secured to one side of the trough 1, and the free ends of sufficient length to permit their being passed across the back and over the shoulder as indicated and thence suitably secured to the trough to support the same.

In the preferred construction shown a slit 6 is formed through that side of the trough to which the straps are attached, and preferably through the secured ends of the

straps as shown, while corresponding slits 7 are formed in the opposite side of the trough. Through these slits or apertures the free ends of the straps 4 are passed after being adjusted to the body, preferably in the manner shown, and are thence bent upward and backward and attached in any suitable manner to the said straps. In the form shown in Fig. 1, this is preferably done by a suitable attaching means 9, which here consist of ordinary safety pins. The advantage of the use of these consist in the fact that they are easily removable in cleansing and sterilizing the device. In the form shown in Fig. 4, suitable button and button hole connections are made on the parts, which are preferably adjustable to regulate the height of the sling when it is attached to the person.

In the preferred form the manner of adjusting the sling is as follows: The arm is placed in the sling with the elbow arranged close to the closed end 2 thereof. The straps 4—4 are then passed up the front side of the body and over the shoulders, and are thence crossed, as shown in Fig. 2, with the free ends passing under the arms, thence through the slits 6 and 7 respectively, and thence bent upward and backward and attached at the proper point upon the straps 4. This method of applying the device may be modified or varied as desired.

The entire device is exceedingly convenient and readily adjustable and different sizes may be made as necessary. It is preferably constructed in a manner by which it may be reversed, the trough being turned inside out so that it may be available for use for either the right or the left arm, and the angle of inclination or declination can be changed by securing the ends at the desired points. When applied as shown the arm is securely held without discomfort of any nature, the solidity of affixation proves of inestimable advantage in cases of children in securing the arm against the annoyances and dangers of escaping parts. It is extremely convenient when the arm is placed in a cast or in splints or dressed in any other manner desirable or necessary.

Having thus described my invention it is obvious that various immaterial modifications may be made in the construction, arrangement or application of the same without departing from the spirit of my invention, hence I do not wish to be understood

as limiting myself to the exact form, construction and arrangement shown and described.

What I claim as new and desire to secure 5 by Letters Patent is:

1. An arm sling comprising a trough-shaped part of suitable material, provided with suspensory slings or straps, each having one end attached to the trough near one 10 end thereof and of suitable length to permit the free end to extend over the shoulder and diagonally across the back to the opposite end of the trough and to be secured thereto.

2. In a device of the kind described and 15 in combination, a reversible trough-shaped member having one end closed and the other end open, and having formed therein near

each end, slits or apertures substantially registering with one another on the opposite side of the trough, and suspensory slings or 20 straps attached to one edge of the trough and of sufficient length to permit the free end to extend over the shoulder and diagonally across the back, thence to be passed through the slits in the trough and bent upward and backward to be attached to said straps. 25

In testimony whereof, I have hereunto signed my name in the presence of two subscribing witnesses.

WILLIAM C. WERMUTH.
